ARITHMETIC LEARNING TOY

Kevin McKibben O'Brien, 296 Main St.,
Westport, Conn. 06880

Filed Jan. 7, 1969, Ser. No. 15,240

Term of patent 14 years

Int. Cl. D19—08

U.S. Cl. D25—1

FIG. 1

FIG. 2

FIG. 1 is a perspective view of an arithmetic learning toy, showing my new design.

FIG. 2 is a perspective view showing the top and sides not shown in FIG. 1.

The particular numerals seen in FIG. 1 are for illustrative purposes.

I claim:

The ornamental design for an arithmetic learning toy, as shown and described.
